SPRAY HEAD FOR AN AEROSOL DISPENSER OR SIMILAR ARTICLE

Theodore Heilig, Long Beach, N. Y.

Application November 23, 1949, Serial No. 6,221

Term of patent 3½ years

(Cl. D58—26)

To all whom it may concern:

Be it known that I, Theodore Heilig, a citizen of the United States, residing at Long Beach, Nassau County, State of New York, have invented a new, original, and ornamental Design for a Spray Head for an Aerosol Dispenser or Similar Article, of which the following is a specification, reference being had to the accompanying drawing, forming a part thereof.

In the drawing:

Fig. 1 is a top plan view of a spray head for an aerosol dispenser or similar article, showing my new design;

Fig. 2 is a side elevational view thereof;

Fig. 3 is a rear elevational view; and

Fig. 4 is a perspective view showing the front thereof.

I claim:

The ornamental design for a spray head for an aerosol dispenser or similar article, substantially as shown.

THEODORE HEILIG.
